UNITED STATES PATENT OFFICE.

ADDISON E. AUGUSTINE, OF HACKENSACK, NEW JERSEY, ASSIGNOR TO CHESTER MACHINE CO. INC., OF NEW YORK, N. Y., A CORPORATION OF NEW YORK.

ELEVATOR CONTROL MECHANISM FOR ENVELOPE-MAKING MACHINES.

Application filed February 24, 1920. Serial No. 360,968.

To all whom it may concern:

Be it known that I, ADDISON E. AUGUSTINE, residing at Hackensack, in the county of Bergen and State of New Jersey, have 5 invented certain new and useful Improvements in Elevator Control Mechanism for Envelope-Making Machines, of which the following is a specification.

This invention relates to an elevator control mechanism, and embodies an improvement over the structure shown and described in pending application Serial No. 315,395, filed August 5, 1919.

An object of the present improvement is 15 to provide an elevator control mechanism including a simple and efficient device automatically operable to lower the elevator when the elevator has been elevated to a given position.

20 A further object is to so design the parts that the elements which are adapted for effecting the lowering of the elevator may be connected with the machine as an attachment so that it may be removed if desired 25 without interfering with the normal operation of the remaining mechanism.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will be 35 indicated in the appended claims.

In the accompanying drawings which are to be taken as a part of this specification, and in which I have shown merely a preferred form of embodiment of the invention:—

40 Figure 1 is a front elevational view of a portion of an envelope-making machine showing parts of the elevator mechanism and having the features of the present invention embodied therein.

45 Figure 2 is an enlarged horizontal sectional view taken substantially upon the plane of line II of Fig. 1.

Figure 3 is a front elevational view of a 50 portion of the structure seen in Fig. 1, the section being taken substantially upon the plane of line III of Fig. 2.

55 Figure 4 is a vertical sectional view taken substantially upon the plane of line IV of Fig. 2.

Figure 5 is a vertical sectional view taken substantially upon the plane of line V of Fig. 2, and

Figure 6 is a detail perspective view of the kicker lever seen in Fig. 2.

Referring to the drawings for describing in detail the structure which is illustrated therein, the reference character L indicates a supporting table which is included in the main frame work of the envelope-making machine. A rotatable cam shaft 2 has a cam 3 fixed to rotate continuously therewith.

Upon a shaft 4 is arranged a bracket 5 providing a pivot support 6 for a rock lever 7 which carries at one end an anti-friction roller 8 in a position to be operated by the cam 3. The opposite end of the lever 7 is pivotally connected, as at 9, with the lower end of a rod 10, the upper end of which has 70 pivotally connected therewith, by means of a pivot pin 11, a pawl 12 being arranged for engaging the teeth of a ratchet 13 fixed upon a shaft 14. The shaft 14 is mounted in an elongated bearing member 15 and carries 75 loosely a crank 16 which in turn supports the pivot pin 11 and pawl 12 so as to maintain the pawl in proper operative association with the teeth of the ratchet at all times.

80 A tension spring 17 is connected to the rock lever 7 so as to urge the roller 8 toward the surface of the cam and at the same time to lift the rod 10 and the pawl 12 whenever the cam turns to permit.

85 The shape of the cam is such that at each rotation a relatively depressed surface portion, as 18, thereof is caused to pass beneath the roller 8. As the surface 18 passes, the pawl 12 will move upwardly for engaging 90 the next succeeding tooth of the ratchet 13. If nothing happens to prevent the pawl 12 will move the ratchet the space of one tooth with each revolution of the cam.

95 A suitable adjustable stop 19 is provided 100 in the lever 7 arranged for engaging the hub 20 of the bracket 5 for positively limiting the upward movement of the pawl.

A worm pinion 21 is carried by the shaft 14 and is disposed to mesh with the teeth of 105 a worm gear 22. The gear 22 is mounted loosely upon a hand wheel shaft 23 and carries one or more pawls 24 disposed for engaging the teeth of a ratchet 25 fixed rigidly with the shaft 23 so that rotation of the 110

shaft 14 will impart a certain degree of rotation to the shaft 23 so long as the pawls 24 are in engagement with the ratchet 25. The shaft 23 is disposed in a horizontal position and is mounted to rotate in bearings 26 provided upon the frame 27 fixed to and depending from the table L. Intermediate the bearings 26 the shaft 23 carries fixed thereto a small gear 28, the teeth of which engage the teeth of a rack bar 29 which is fixed to the elevator 30. The elevator has opposite guide portions 31 received within appropriate vertical guide slots 32 provided by the frame 27, and the engagement between the rack-bar and the gear 28 is designed for supporting and for moving the elevator upwardly in accordance with the rotation imparted to the shaft 23 from the shaft 14 through the worm pinion and gear 21 and 22.

20 A suitable surface, as 33, is provided upon the elevator for receiving a pile, as 34, of envelope blanks to be fed continuously upwardly so that the upper level of the pile is maintained during the operation of the machine.

25 The pawls 24 are pivotally mounted, as at 35, upon the relatively outer surface of the worm gear 22 so that their free ends are adapted to swing toward and away from the center line of the shaft 23, and into and out of engagement with the teeth of the ratchet 25, which teeth project radially from said ratchet. Each of the pawls carries a finger 36 which extends through openings 37 in the gear 22 and which project somewhat beyond the inner or rear surface of said gear substantially as indicated. Tension springs 38 engage the inner ends of the fingers for urging the pawls normally into engagement with the teeth of the ratchet.

30 Between the gear 22 and the adjacent surface 39 of the frame 27 is arranged a collar 41 slidable longitudinally of the shaft 23. This collar is formed with an annular groove 41 within which engages the fingers 42 of a hand operable yoke 43 by which to move the collar back and forth along the shaft 23. The forward end of the collar 40 is bevelled off to provide a cone-shaped surface 44 disposed for engaging the ends of the fingers 36 whenever the collar is moved toward said fingers.

35 The yoke 43 is connected with a pivot pin 45 carried by the frame 27 and is fitted with 55 an appropriately extended handle part 46 by which to move the collar at will.

40 When the collar is in the position, as shown in Fig. 2 of the drawings; that is, when it is free of engagement with the fingers 36, the springs 38 are free to exercise their function of holding the pawls 24 in engagement with the teeth of the ratchet 25. But when the handle 46 is swung to move the collar forwardly then the cone surface 44 of the collar presses the fingers 36

radially outwardly and positively lifts and holds the pawls out of engagement with the teeth of the ratchet 25.

45 Whenever the pawls are lifted out of engagement with the ratchet 25, the gear 22 will rotate idly about the shaft 23 and will impart no rotation to said shaft. By this simple arrangement it becomes unnecessary to stop the operation of the entire machine when for any reason it becomes desirable only to stop the upward movement of the elevator.

50 The fact that the cone surface 44 is annular enables it to properly cooperate with the fingers 36 irrespective of the rotary position of the fingers relative to said surface. At the same time, the gear 22 with said fingers will be allowed to rotate freely with said fingers around the cone surface.

55 A hand wheel G is fixed to the outer end of the shaft 23 so that said shaft may be turned at will whenever it is desired to move the elevator irrespective of the automatic driving mechanism just described. When it is desired to rotate the shaft for lowering the elevator it is necessary first to move the handle 46 for disconnecting the pawls 24 from the ratchet 25. The pawls 24, while in engagement with the teeth of the ratchet 25, prevent rotation of the shaft 23 under the weight of the elevator 30. When, however, the handle has been moved sufficiently to disconnect the pawls 24 from the ratchet the weight of the elevator will cause the elevator to fall at once to its lowest position, the shaft 23 with the ratchet 25 meanwhile turning idly in its bearings.

60 Whenever it is desired to raise the elevator, this may be done without disconnecting the pawls since rotation of the shaft in a direction for lifting the elevator will simply cause the teeth of the ratchet 25 to click backwardly beneath the ends of the pawls.

65 With the mechanism as thus far described, it will be apparent that rotation of the cam 3, and the consequent step by step rotation of the shaft 14, will cause the elevator to be lifted one step at each rotation of the cam while the pawls 24 are in cooperative relation with the ratchet 25.

70 Suitable mechanism may be provided, if desired, for influencing the rotation of the shaft 14 so as thus to prevent rotation of said shaft when the top level of the pile 34 of blanks is at a sufficient elevation. This mechanism, as well as the mechanism herein above set forth, is fully described in pending application Serial No. 315,395, filed August 5, 1919, and consists in a feeler lever H pivotally mounted intermediate its ends, as at 47, in a standard 48 carried by the table L. This feeler member has an end surface 49 for resting upon the upper surface 50 of the pile of envelope blanks. The opposite end of the feeler is pivotally con-

nected, as at 51, to the upper end of a rod 52 which rod extends downwardly into pivotal connection with the pivot pin 11 already described as carrying the pawl 12.

5 Although the cam 3 will rotate continuously, yet the lever H will prevent the rod 10 from moving upwardly the full distance with any rotation of the cam which occurs while the level 50 of the blanks is sufficiently high to hold the rods 10 and 52 against movement above a given point. The pawl 12 will operate to move the ratchet 13 and shaft 14 only when the rod 10 is allowed to move upwardly to said given point.

10 15 Accordingly, what may be termed idle and active operations of the pawl 12 may take place at intervals while the blanks are being removed from the pile 34 during the operation of the machine.

20 25 The worm wheel 22, being loose upon the shaft and being adapted to be connected to and disconnected from the shaft at the will of the operator, is hereinafter referred to as the drive wheel for the shaft.

30 35 After the machine has operated for a sufficient time so that all, or nearly all, of the blanks upon the elevator have been removed, and the elevator is, therefore, substantially in its highest position, it is desirable that the elevator move automatically out of this position and preferably to its lowest position ready to receive a further pile of blanks. This not only saves the operator the time and trouble of manually lowering the elevator, but it also serves as a simple and effective indication to the operator that his machine requires replenishing. Where a battery of machines is being operated the falling of the platforms constitutes a particularly appropriate and effective means of notification to the operator.

40 45 As above mentioned it is a particular object of the present invention to provide means for accomplishing the automatic falling of the elevator. While any appropriate mechanism may be employed for producing this result the structure illustrated herein, as an example, includes a kicker lever 53 fashioned substantially as indicated in the 50 perspective view Fig. 6. It is provided with spaced pivot portions 54 adapted to straddle the supporting bracket piece 55 of the yoke 43 and to receive and pivot upon the opposite end portions of the pivot pin 45. A 55 portion 56, connecting together the pivot portions 54, is off-set and is positioned to overlap and engage against the inner side of the yoke 43. The main portion of the lever extends through an opening 57 formed in 60 the adjacent wall of the frame 27, and has connected therewith a tension spring 58 arranged normally to swing the lever so that the portion 56 forces the spread end of the yoke 43 outwardly.

65 A latch lever 59 is pivotally mounted, as

at 60, upon a bracket piece 61 and has its free end 62 arranged in the path of an operating pin 63 which is carried by the platform 30. The latch lever extends over the inner end of the lever 53 and normally rests 70 upon the upper surface of the lever 53. A suitable shoulder 69 is formed in the under surface of the lever 59 for engaging over the edge portion 70 of the lever 53 to retain the lever 53 against the tension of the spring 58. 75

The relation of the parts is such that when the elevator has reached a predetermined elevation the stop pin 63 will engage and lift the lever 59 so that the shoulder 69 will be carried out of the path of the lever 53. 80 The spring 58 will immediately snap the lever 53 over so that the spread end of the yoke 43 will carry the collar 40 outwardly and disengage the pawls 24 from the ratchet 25 in substantially the same manner as said 85 collar would be moved by the manual operation of the handle 46, as above described.

The elevator being thus caused to fall the operator replenishes the supply of blanks upon the elevator, and returns the 90 lever 53 to position behind the shoulder 69 of the latch lever. He may move the elevator up to a suitable starting point if he desires by manual operation of the handle G.

When the elevator is in its lowered position the lower end 71 of the rack 29 rests 95 upon the upper surface of the anvil 72.

The operation of returning the lever 53 to its retained position is effected by movement of the handle 46 which, at the same time, moves back the collar 40 allowing the pawls 24 to move into engagement with the ratchet 25. Here it should be particularly noted that when the lever 53 is in its retained position the yoke 43 is entirely free 100 to move the collar 40 by means of the handle 46 at any time without effecting the position of the lever 53.

105 It should also be noted that whenever the latch lever 59 is lifted so that the lever 53 is unlatched, the resultant movement of the collar 40, under the impulse of the spring 58, is accomplished almost instantaneously. The movement of the pawls from their fully engaged position with the teeth of the 110 ratchet to their fully disengaged position, is thus accomplished so quickly that the amount of wear produced by the frequent engagement and disengagement of the pawls is reduced to a minimum.

115 If desired a hardened detachable wear plate 64 may be connected with the lever 53 in a position for engaging the shoulder 69 of the latch lever 59, thus reducing wear to a minimum at this point.

120 125 The stop pin 63 is preferably connected with the elevator adjustably. For this purpose the body plate of the elevator may be provided with a slot 65, the stop pin being provided with a rectangular extension 66 ex-

tending through said slot and being held by a clamp nut 67 threaded upon its opposite end. The stop pin has its operating surface, as 68, preferably rounded so as to more effectively cooperate with the end of the latch lever, and the rectangular portion 66 is of a size to fit nicely within the slot 65 so that the rounded surface of the stop pin will be maintained in proper position at all times.

10 As many changes could be made in this construction without departing from the scope of the invention as defined in the following claims, it is intended that all matter contained in the above description, or shown 15 in the accompanying drawings, shall be interpreted as illustrative only and not in a limiting sense.

Having thus described my invention, what I claim as new and desire to secure by Letters Patent is:—

1. In elevator control mechanism for envelope making machines, an elevator adapted for supporting a pile of envelope blanks, means for moving the elevator upwardly including a rotatably mounted shaft, a ratchet fixed to said shaft, a drive member rotatable about said shaft, a part carried by the mentioned drive member yieldingly engaging said ratchet whereby rotation of the 30 drive member will drive the shaft, means to rotate the drive member, a manually operable member operable to move said part at will out of engagement with said ratchet to thereby disconnect the driving member from 35 said shaft to permit downward movement of the elevator, and means automatically operable also to effect movement of said manually operable means when the elevator has reached a predetermined elevation.

40 2. In elevator control mechanism for envelope-making machines, an elevator adapted for supporting a pile of envelope blanks, means for moving the elevator upwardly including a rotatably mounted shaft, a ratchet fixed to said shaft, a drive member rotatable about said shaft, a part carried by the mentioned drive member yieldingly engaging said ratchet whereby rotation of the drive member will drive the shaft, means to rotate 50 the drive member, and means automatically operable to move said part out of engagement with said ratchet to thereby permit downward movement of the elevator when the elevator has reached a predetermined 55 elevation.

3. In elevator control mechanism for envelope-making machines, an elevator adapted for supporting a pile of envelope blanks, means for moving the elevator upwardly including a rotatably mounted shaft, a drive wheel for the shaft mounted loosely upon the shaft, a ratchet wheel fixed to the shaft, a pawl carried by the drive wheel at one side thereof yieldingly engaging the ratchet wheel, a finger extending from the pawl

through an opening in the drive wheel to the opposite side of said drive wheel, and means automatically operable move into engagement with said finger for disengaging the pawl from the ratchet.

4. In elevator control mechanism for envelope-machines, an elevator for supporting a pile of envelope blanks, means for moving the elevator upwardly including a rotatably mounted shaft, a drive wheel for the shaft, a ratchet wheel fixed to the shaft, a pawl carried by the drive wheel at one side thereof adapted to engage the drive wheel, a finger extending from the pawl through an opening in the drive wheel to the opposite side of said drive wheel, means engaging said finger at said opposite side of the drive wheel for yieldingly maintaining the pawl in engagement with the ratchet wheel, and means also at the opposite side of the drive wheel automatically operative upon said finger for disengaging said pawl from said ratchet.

5. In elevator control mechanism for envelope-making machines, an elevator adapted to support a pile of envelope blanks, lifting means for lifting the elevator upwardly including a ratchet and a pawl engaging with the ratchet, said pawl being disengageable from the ratchet to render the lifting means inoperative, and snap acting means to move the pawl quickly from a fully engaged position to a fully disengaged position relative to the ratchet.

6. In elevator control mechanism for envelope-making machines, an elevator adapted to support a pile of envelope blanks, lifting means for lifting the elevator upwardly including a ratchet and a pawl engaging with the ratchet, said pawl being disengageable from the ratchet to render the lifting means inoperative, snap acting means to move the pawl quickly from a fully engaged position to a fully disengaged position relative to the ratchet, and means whereby said snap acting means is automatically caused to operate for disengaging the pawl when said elevator has reached a pre-determined elevation.

7. In elevator control mechanism for envelope-making machines, the combination with an elevator adapted for supporting a pile of envelope blanks, means for moving the elevator upwardly, and manually operable means for rendering the lifting means operative and inoperative at will, of a part mounted to move independently of said manually operable means, a spring engaging said part tending to urge said part into position for moving said manually operable means to position rendering the lifting means inoperative, an element restraining said part against such movement, and means whereby said element is operable to release said part when the elevator reaches a predetermined elevation.

8. In elevator control mechanism for envelope-making machines, the combination with an elevator adapted for supporting a pile of envelope blanks, means for moving the elevator upwardly, and manually operable means for rendering the lifting means operative and inoperative at will, of a part mounted to move independently of said manually operable means, a spring engaging said part tending to urge said part into position for moving said manually operable means to position rendering the lifting means inoperative, a pivotally mounted lever arranged adjacent said part having a shoulder thereon normally restraining said part against such movement, and means whereby said lever will be swung to release said part when the elevator reaches a predetermined elevation.
9. In elevator control mechanism for envelope-making machines, the combination with an elevator adapted for supporting a pile of envelope blanks, means for moving the elevator upwardly, and a pivotally mounted hand lever operable for rendering the lifting means operative and inoperative at will, of a second pivotally mounted lever adjacent said hand lever normally not interfering with the movements of the hand lever, means urging said second lever to position for causing movement of the hand lever, a third lever, and means whereby said third lever is operable to permit

movement of the second lever when the elevator reaches a given elevation. 35

10. In elevator control mechanism for envelope-making machines, the combination with an elevator adapted for supporting a pile of envelope blanks, means for moving the elevator upwardly, and a pivotally mounted hand lever operable for rendering the lifting means operative and inoperative at will, of a second pivotally mounted lever adjacent said hand lever normally not interfering with the movements of the hand lever, means urging said second lever to position for causing movement of the hand lever, a third pivotally mounted lever, said third lever having a shoulder thereon standing to restrain the second lever against its 45 movement, said third lever also having a portion extending to adjacent the elevator, an abutment piece carried by the elevator to strike said portion of the third lever to move the third lever to disengaging position when the elevator reaches a given elevation, and means whereby said abutment piece is adjustable for the purpose 50 set forth.

In testimony whereof I affix my signature 60 in the presence of two witnesses.

ADDISON E. AUGUSTINE.

Witnesses:
